United States Patent Office

Des. 178,430
Patented July 31, 1956

178,430

INDEX CARD HOLDER

Jacob S. Sherman, Chicago, Ill., assignor to Park Sherman
Company, Chicago, Ill., a corporation of Illinois

Application March 28, 1955, Serial No. 35,242

Term of patent 14 years

(Cl. D74—1)

FIG. 1

FIG. 2

FIG. 3

FIG. 4

Fig. 5Fig. 6Fig. 1 is a top plan view of an index card holder showing my new design;

Fig. 2 is a side elevational view thereof;

Fig. 3 is a rear elevation view;

Fig. 4 is an elevational view showing the side opposite to that shown in Fig. 2;

Fig. 5 is a top perspective view; and

Fig. 6 is another perspective view looking in the opposite direction from that shown in Fig. 5.

The essential features of my design reside in the portions shown in solid lines on the drawing.

I claim:

The ornamental design for an index card holder, substantially as shown and described.
